UNITED STATES PATENT OFFICE.

WILLIAM C. CARTER, OF ST. LOUIS, MISSOURI.

AUTOMATIC TEMPERATURE REGULATOR FOR INTERNAL-COMBUSTION ENGINES.

Application filed April 30, 1918. Serial No. 231,659.

To all whom it may concern:

Be it known that I, WILLIAM C. CARTER, a citizen of the United States, residing at St. Louis, Missouri, have invented a certain 5 new and useful Improvement in Automatic Temperature Regulators for Internal-Combustion Engines, of which the following is a full, clear, and exact description, such as will enable others, skilled in the art to which 10 it appertains, to make and use the same.

This invention relates to internal combustion engines of the kind that comprise a shutter mechanism or similar means for controlling the supply of air used to absorb 15 heat from the heat radiating means of the engine, and an automatically-operating means for controlling said shutter mechanism so as to increase or decrease the supply of air as the temperature of the engine 20 varies.

One object of my invention is to provide an internal combustion engine of the general type above referred to, in which the automatic means that controls the shutter mechanism 25 consists of a thermostat that is operated by the heat which radiates from the radiator of the cooling system of the engine, which thermostat is combined with the shutter mechanism so as to form a single 30 unit that can be applied easily to the radiator of the automobile.

Another object is to provide an internal combustion engine which is equipped with an electrically-operated temperature regulator 35 that consumes very little electric current and which is so constructed that there is no possibility of the circuit controlling means remaining in such a condition that the energizing circuit will remain closed 40 long enough to exhaust the battery.

And still another object is to provide an internal combustion engine which has an efficient temperature regulator of simple construction that comprises a shutter mechanism 45 or similar means for controlling the passage of air through the radiator of the cooling system, a mechanical means for holding the shutters or slats of said mechanism in adjusted position, an electrically-operated means for moving said shutters or slats and a thermostat governed circuit controlling means constructed in such a manner that the circuit which energizes said electrically-operated means will be opened auto-

matically each time said means effects a 55 change in the position of said shutter mechanism. Other objects and desirable features of my invention will be hereinafter pointed out.

Figure 1 of the drawings is a front elevational view of an automatic temperature regulator for internal combustion engines constructed in accordance with my invention.

Figure 2 is a vertical sectional view of 65 said regulator, showing it applied to a radiator that forms part of the water cooling system of the engine.

Figure 3 is a rear elevational view of the 70 regulator.

Figure 4 is a perspective view of one of the slats or shutters of the shutter mechanism; and

Figure 5 is a side elevational view, illustrating a slight modification of my invention.

Referring to Figures 1 to 4 of the drawings, which illustrate one form of my invention, A designates a radiator such as is generally used in connection with water 80 cooled internal combustion engines for cooling the water that is used to absorb heat from the cylinders of the engine, and B designates a shutter mechanism that is used for controlling the passage of air through 85 the radiator A, said shutter mechanism comprising slats or shutters 1 which are adapted to be closed so as to diminish or cut off the flow of the air through the radiator when the engine is cold or at a low temperature, and thereafter opened to resume or 90 increase the flow of the air through the radiator when the temperature of the engine rises. The shutter mechanism B preferably comprises a frame or casing 2 which 95 is so constructed that it can be slipped over or easily connected in any other suitable manner to the shell of the radiator A, and the slats or shutters 1 are preferably arranged horizontally and pivotally mounted 100 in flanges 3 that project forwardly from the front side of the frame or casing 2, as shown in Figure 4. In order to prevent the slats 1 from rattling and also enable said slats to be mounted easily in the frame 105 B, I prefer to provide each slat at one end with a rigid trunnion 4 and at its opposite end with a spring-pressed trunnion 5, both

of which have tapered or pointed ends that project into horizontally-aligned holes in the flanges 3 on the frame 2. If desired, each slat can be provided with a pressed rib 6 of semi-circular shape in cross section, so as to reinforce and strengthen the slat and also provide a convenient means for attaching the trunnions to the slat, the rigid trunnion 4 being seated in the pressed rib 6 and soldered in position, and the spring-pressed trunnion being mounted in a tubular bearing 5^a that is seated in the rib 6 and securely soldered in position. The slats 1 are connected together by an operating bar C that is pivotally connected to rearwardly-projecting arms 7 on the slats 1, as shown clearly in Figure 2, said operating bar being adapted to be moved downwardly to open the slats or shutters 1 and upwardly to close said slats. The means for automatically governing the slats 1 of the shutter mechanism preferably consists of an electrically-operated mechanism that comprises electro-magnets or solenoids that are connected by means of an actuating device with the operating bar C of the shutter mechanism, a thermostat arranged so that it will be rendered operative either by the heat that radiates forwardly from the radiator A of the cooling system or by the heat inside of the hood that encloses the engine, and contacts arranged in the circuits that energize said magnets or solenoids, said contacts being combined with the actuating device and the thermostat in such a manner that it will be impossible for the energizing circuit to remain closed long enough either to consume a considerable amount of current or to exhaust the battery in said circuit. In the form of my invention shown in Figures 1 to 3, inclusive, the electrically-operated means that governs the shutter mechanism is mounted on the frame or casing 2 of the shutter mechanism so as to form a self-contained temperature regulator that can be easily applied as a single unit to the radiator A of the cooling system. Said electrically-operated means preferably consists of an actuating device D consisting of a bell crank lever pivotally mounted on the frame 2 of the shutter mechanism at the rear of the slats 1 and having its horizontal arm pivotally connected at 8 to the upper end of the operating bar C. The vertical arm of said bell crank lever is pivotally connected at its lower end to a rod 8^a which is formed integral with or connected in any other preferred manner to the cores of two solenoids E and F. When the solenoid E is energized the bell crank lever or actuating device D swings in a direction to move the operating bar C downwardly so as to open the shutters 1, and when the solenoid F is energized, said actuating device swings 65 in the opposite direction so as to close said shutters or move them towards their closed position. The circuits in which the solenoids E and F are arranged are controlled by a thermostat G that co-operates with contacts 10 and 11 which are mounted on a bifurcated portion of the actuating device C, as shown in Figure 3, the contact 10 being connected by means of a wire 10^a with the solenoid E, and the contact 11 being connected by means of a wire 11^a with the solenoid F. The thermostat G is connected by means of a wire 12 with a battery 13 or other source of electrical energy, and the other side of said battery is connected by means of branches 13^a and 13^b with the solenoids E and F, respectively. Any suitable form of thermostat may be used, but I prefer to use a thermostat formed from two strips of metal which have different co-efficients of expansion; for example, a strip of brass *x* and a strip of steel *y* that are connected together in such a manner that they form a resilient arm which tends to buckle or assume a curved shape when it is heated by the heat that radiates from the radiator A. In order that the thermostat G may be adjusted so as to accurately regulate the opening and closing of the shutters 1, I have pivotally connected the thermostat at 14 to the frame 2 and have arranged an adjusting screw 15 and a spring 16 on the opposite sides of the pivot of the thermostat, as shown in Figure 3, so as to enable the free end of the thermostat to be set properly with relation to two stationary stops 17 and 18 that limit the movement of the thermostat in opposite directions. Assuming that the thermostat G is so adjusted that it will bear against the stationary stop 17 when the slats 1 of the shutter mechanism are closed and the engine with which the regulator is used is cold, the heat that radiates from the radiator A when the engine is set in operation will cause the free end of the thermostat G to flex upwardly into engagement with the contact 10, thereby closing the circuit in which the solenoid E is arranged. As soon as the solenoid E is energized the core of same will move to the right, and thus cause the actuating device D to push the operating bar C downwardly and open the slats 1 partially. Owing to the fact that the contact 10 is carried by the actuating device D, which moves as soon as the solenoid E is energized, the circuit in which the solenoid E is arranged will be closed only for an instant and thereafter immediately opened, thus consuming very little electric current. The slats 1 and actuating device D are locked securely in the position into which they have been moved by means of a spring-pressed detent 19 that co-operates with the rod 8^a to which the lower end of the vertical arm of the actuating device D is piv- 130

totally connected. Consequently, the contact 10 will remain spaced away from the thermostat until the condition of the thermostat again changes. As the temperature of the 5 engine increases more heat will radiate from the radiator A, thus raising the temperature of the thermostat G and causing it to buckle more or flex towards the contact 10, and as soon as the thermostat engages said contact 10 the solenoid E again becomes operative and moves the actuating device D in a direction to push the operating bar C downwardly, so as to open the slats 1 a trifle farther, the circuit in which the solenoid E is 15 arranged being broken as soon as the actuating device D starts to move. By the time the slats 1 have been fully opened, the thermostat G will be in engagement with the stop 18, the actuating device D being then held 20 in such a position by the spring detent 19 that it is impossible for the thermostat to again engage the contact 10, even though the temperature of the thermostat becomes abnormal, due to overheating of the engine, 25 from some abnormal condition, as, for example, insufficient lubrication. When the temperature of the engine decreases the heat that radiates from the radiator will decrease or diminish and immediately thereafter the 30 thermostat will tend to straighten out. In flexing back to its normal condition the thermostat will engage the contact 11 and close the circuit in which the solenoid F is arranged, thereby causing the actuating device D to swing in a direction so as to move the operating bar C upwardly and move the shutters 1 towards their closed position. As the heat from the radiator diminishes the thermostat will gradually straighten out 35 and cause the shutters 1 to be moved step by step into their closed position, the stationary stop 17 being so arranged that it will hold the thermostat G spaced away from the contact 11 when the shutters 1 are 40 completely closed.

While I prefer to mount the thermostat, the actuating device and the magnets or solenoids on the frame 2 of the shutter mechanism, so as to form a self-contained 45 temperature regulator that can be applied as a single unit to the radiator of the cooling system, it is not essential that the electrically-operated controlling means be arranged in this manner, for if desired, said 50 means can be arranged at the rear of the radiator underneath the hood that encloses the engine. In Figure 5 of the drawings I have illustrated a temperature regulator constructed in this manner and comprising 55 two solenoids E' and F', an actuating device D' connected by means of a link with the operating bar of the shutter mechanism and a thermostat G' for controlling the circuit in 60 which said solenoids are arranged.

65 Having thus described my invention, what

I claim, and desire to secure by Letters Patent, is:

1. A temperature regulator for engines, comprising a shutter mechanism arranged in proximity to the engine for regulating the supply of air used to cool the engine, an actuating device for said mechanism, solenoids for moving said device in opposite directions, spaced contacts on said actuating device, each of which is electrically connected to one of said solenoids, a thermostat connected to a source of electrical energy and interposed between said contacts, and means for limiting the movement of said thermostat in opposite directions. 75

2. A temperature regulator for engines, comprising a shutter mechanism arranged in proximity to the engine for regulating the supply of air used to cool the engine, an actuating device for said mechanism, solenoids for moving said device in opposite directions, spaced contacts on said actuating device, each of which is electrically connected to one of said solenoids, a thermostat connected to a source of electrical energy and interposed between said contacts, means for limiting the movement of said thermostat in opposite directions, and a spring-pressed detent that holds said actuating device normally at rest. 95

3. A temperature regulator for engines, comprising a shutter mechanism arranged in proximity to the engine for regulating the supply of air used to cool the engine, an actuating device for said mechanism, solenoids for moving said actuating device in opposite directions, spaced contacts on said actuating device, each of which is electrically connected to one of said solenoids, a thermostat connected to a source of electrical energy and interposed between said contacts, means for limiting the movement of said thermostat in opposite directions, a spring-pressed detent that holds said actuating device normally at rest, and means for 100 adjusting the thermostat relatively to the means that limits the movement of same in opposite directions. 105

4. A temperature regulator for engines, comprising a shutter mechanism arranged in proximity to the engine for regulating the supply of air used to cool the engine, a pivotally-mounted, bell-crank-shaped actuating device for said mechanism provided with a bifurcated portion equipped with contacts 115 that form parts of independent electric circuits, solenoids in said circuits having their cores connected together by a rod which is pivotally connected to one arm of said actuating device, a spring-pressed detent that 120 co-operates with notches in said rod, and a thermostat arranged between said contacts for closing the circuits in which said solenoids are arranged. 125

WILLIAM C. CARTER.
